UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed February 10, 1925. Serial No. 8,202.

My invention relates to electric furnaces and particularly to electric muffle furnaces.

One object of my invention is to provide a convenient and practical means for mounting 5 a resistor in an electric muffle furnace.

Another object of my invention is to provide a work-receiving chamber in an electric furnace that is muffled from the heat of an electric resistor.

10 A still further object of my invention is to provide an electric furnace having a work-receiving chamber therein comprising a plurality of sections, each section having a resistor supporting means associated therewith 15 whereby the resistor or other parts associated in each section may be readily removable from the furnace.

In practicing my invention, I provide a furnace chamber comprising a plurality of 20 refractory walls of any well known structure. A work-receiving chamber is located 25 therein having a plurality of sections cooperating in end-to-end relation to form a substantially elongated chamber. Each section 30 is composed of a plurality of metallic interlocking castings, each being designed to support a refractory resistor supporting member thereon. A resistor member is associated with each section of the work receiving 35 chamber and interlocks with the resistor supporting member in a manner to be hereinafter more fully described.

The metallic, interlocking castings are so 40 designed that resistor-supporting members 35 may be located both above and below the work-receiving chamber enclosed thereby. The resistor-supporting members associated 45 with the lower portion of the work-receiving chamber also serve to support the entire work-receiving chamber structure. The resistor members employed for heating the work-receiving chamber may be of any practical design, but I prefer to use one comprising a plurality of preformed parallel-extending return-bent convolutions, although I do not wish to be limited to this type of 50 resistor member.

In the single sheet of drawing,

55 Figure 1 is a view, partially in vertical section and partially in elevation, of a furnace embodying my invention; and

Fig. 2 is a view, partially in longitudinal section and partially in elevation of the furnace shown in Fig. 1.

60 A furnace 11 comprises a plurality of

walls 12 enclosing a furnace chamber 13. One of the walls 12 comprises a slot 14 whereby work may be introduced into the chamber 13 or work received therefrom. Any desirable means may be employed for 60 this purpose as it constitutes no part of my invention.

A refractory metallic casting member 15 interlocks with a similar casting member 16 to form a section 17 of a work receiving 65 chamber 18. The castings 15 and 16 have integral flange members 19 and 20, respectively, that are shaped to form a longitudinally extending portion of substantially 70 channel form and adapted to receive resistor-supporting members 21 and 22.

The resistor-supporting members 21 and 22 comprise a pair of abutting, cooperating, 75 ceramic refractory members 23 and 24 that are locked together by pin members 25 that extend substantially transversely therethrough. The refractory members 23 and 24 are of substantially L-shape and cooperate in operative position to form the resistor-supporting member 21 that is of substantially T-shape. The resistor-supporting member 21 is adapted to cooperate with the flange members 19 and 20 of the casting 80 members 15 and 16.

Resistor members 26 and 27 are supported by refractory resistor supporting members 21 and 22 in a manner that will now be described. Each of the refractory members 23 and 24 that cooperate to form the refractory resistor supporting members 21 85 and 22 has a plurality of slots 28 that extend inwardly from the upper face of the resistor supporting members 21 and from the lower face of the resistor supporting members 22. The slots 28 have offset portions 29 90 at the innermost end thereof that are of sufficient size to receive the convolutions of the resistor members 26 and 27.

By alining the edge portions of the slots 28, the resistor members 26 and 27 are introduced therewith, and a longitudinal movement of the members 23 and 24 relatively to each other permits the resistor members 26 and 27 to be inserted into the offset portions 29 associated therewith. The pin members 25 are then inserted to secure the refractory members 23 and 24 from further longitudinal movement, and the resistor members 26 and 27 are thereby securely interlocked with the refractory supporting members 21 and 22. 105 110

This method of interlocking the resistor members 26 and 27 with the refractory supporting members 21 and 22 is specifically set forth in my copending application Serial No. 5 4236 filed Jan. 28, 1925, (Case No. 11,709) and which is assigned to the Westinghouse Electric and Manufacturing Company.

The structure as hereinbefore set forth represents a complete unit comprising a plurality of interfitting castings which inclose a work-receiving chamber 18 and which serve to support refractory resistor-supporting members 21 and 22 that are interlocked with a pair of resistor members 26 and 27, the 10 walls 31 and 32 of the work-receiving chamber 18 serving to muffle the work passing therethrough from the direct heat rays of the resistor members 26 and 27. Any desired number of unitary sections may be employed 15 depending upon the nature of the work passing therethrough and I have shown a plurality of removable sections 17 and 33 that are placed in cooperating end to end relation. A structure of this nature may be 20 readily employed for heat treating a plurality of metallic members 34 that are drawn therethrough for the purpose set forth.

Various modifications and changes may be made without departing from the spirit and 25 scope of the invention, therefore, only such limitations shall be placed thereon as are imposed by the prior art or are set forth in the appended claims.

I claim as my invention:

35 1. In an electric furnace, the combination with a plurality of refractory walls enclosing a furnace chamber, and a muffle located therein, of an electric resistor member supported by said muffle in spaced relation 40 therefrom.

2. In an electric furnace, the combination with a plurality of refractory walls forming a furnace chamber, a muffle located within said chamber and spaced from the walls 45 thereof, and means carried by said muffle for supporting resistor members thereon, certain of said means also serving to space said muffle above the floor of said furnace.

3. In an electric furnace, the combination 50 with a plurality of refractory walls enclosing a furnace chamber, and a muffle located

therein comprising a plurality of cooperating sections located in end to end relation, of a plurality of refractory members severally supported by said sections and a plurality of 55 resistor members severally supported by said refractory member.

4. In an electric furnace, the combination with a plurality of refractory walls enclosing a furnace chamber, of a plurality of 60 muffle members located therein and forming a work-receiving chamber, said muffle members being disposed in cooperating interlocked relation.

5. In an electric furnace, the combination 65 with a plurality of refractory walls enclosing a furnace chamber and a plurality of muffle members located therein and forming a work-receiving chamber, said muffle members being disposed in cooperating interlocked 70 relation, of a plurality of refractory resistor-supporting members interlocked with said muffle members.

6. In an electric furnace, the combination 75 with a plurality of refractory walls enclosing a furnace chamber, a plurality of muffle members located therein and forming a work-receiving chamber, said muffle members being disposed in cooperating interlocked relation, and a plurality of refractory resistor-supporting members interlocked with said 80 muffle members, of a resistor interlocked in operative position with said refractory members.

7. In an electric furnace, the combination 85 with a plurality of refractory walls enclosing a furnace chamber, a plurality of muffle members located therein and forming a work-receiving chamber, said muffle members being located in interlocked sections extending 90 in cooperative end-to-end relation, and a plurality of refractory resistor-supporting members having a plurality of slots located 95 therein supported by said muffle members, of a resistor located in said slots and interlocked in operative position with said refractory member.

In testimony whereof, I have hereunto subscribed my name this 9th day of February, 1925

ALVIN D. KEENE.
